CLAIM

The ornamental design for grater teeth, as shown and described.

DESCRIPTION

FIG. 1 is a perspective view of the grater teeth showing our new design.

FIG. 2 is a bottom plan view thereof.

FIG. 3 is a left side view thereof.

FIG. 4 is a top plan view thereof.

FIG. 5 is a front view thereof.

FIG. 6 is a right side view thereof.

FIG. 7 is a rear view thereof.

FIG. 8 is a front view thereof, an array of the grater teeth shown in broken lines for illustrative purposes only and form no part of the claimed design.

FIG. 9 is a front perspective view of the grater teeth, the broken lines representing the array of grater teeth and the grater for illustrative purposes only and form no part of the claimed design; and,

FIG. 10 is a front view of the grater teeth, the broken lines representing the array of grater teeth and the grater for illustrative purposes only and form no part of the claimed design.

The broken lines shown in the figures depict portions of the grater teeth that form no part of the claimed design.
